Fred Booss

United States Patent Office.

FREDERICK BOOSS, OF NEW YORK, N. Y.

Design No. 2,907, dated February 4, 1868.

DESIGN FOR A MUFF.

The Schedule referred to in these Letters Patent and making part of the same.

ALL WHOM IT MAY CONCERN:

Be it known that I, FREDERICK Booss, of the city, county, and State of New York, have invented a new improved Muff; and I do hereby declare that the following is a full, clear, and exact description thereof, which will enable those skilled in the art to make and use the same, reference being had to the accompanying drawings, forming part of this specification, in which the drawing represents a perspective view of my improved Muff.

This invention relates to a new design for a muff, which has an outer covering, A, of velvet, cloth, or otherable fabric, lined at the edges with a fur border, B, as shown. The complete fur, C, of a marten or otherable animal, is laid and fastened around the muff, in such a manner that the end of the head, a, is close to under the root of the tail, b, of the fur, as is clearly shown in the drawing, while the legs c c extend from sides of the fur C towards the ends of the muff, in the manner indicated in the drawing, the tail b being extended loosely from the muff.

I claim as new, and desire to secure by Letters Patent—

The design for muffs herein set forth and shown.

FRED. BOOSS.
